UNITED STATES PATENT OFFICE.

FRANK W. CARLSON, OF CHICAGO, ILLINOIS.

CLOSET BEND OR CONNECTION.

986,905.

Specification of Letters Patent. Patented Mar. 14, 1911.

Application filed July 16, 1909. Serial No. 507,884.

REISSUED

To all whom it may concern:

Be it known that I, FRANK W. CARLSON, a citizen of the United States, residing at Chicago, in the county of Cook and State of Illinois, have invented new and useful Improvements in Closet Bends or Connections, of which the following is a specification.

Heretofore pipe bends or connections have been made open at both ends and after being attached to the drainage system of a building 10 attached to the drainage system of a building they are plugged at the end which is connected to the closet bowl so that the system can be tested before the building is plastered and to prevent rubbish from falling 15 into the connection. It happens sometimes that one or more of these plugs will be blown out or removed and this will let the water drain off and spoil the test. While the work is going on in the building it also happens 20 with more or less frequency that the plugs are knocked out or deliberately removed and rubbish falls or is thrown into the bend or connection which eventually causes a great deal of trouble in the drainage system.

One of the objects of this invention is to 25 provide a stock closet bend or connection of simple and inexpensive construction which can be easily and quickly made to fit in place beneath any floor.

Another object of the invention is to 30 provide means to facilitate setting or fitting the closet bowl in place and securely locking it to the closet bend or connection.

In the accompanying drawings illustrating 35 the preferred embodiment of my invention Figure 1 is a top plan view of the closet bend or connection. Fig. 2 is a side elevation thereof. Fig. 3 is a detail enlarged 40 sectional view on the line 3—3 of Fig. 1 showing the cap. Fig. 4 is a vertical central sectional view. Fig. 5 is a detail enlarged 45 sectional view showing the means for locking the closet bowl and bend or connection together. Figs. 6 and 7 are sectional views on the lines 6—6 and 7—7 of Fig. 5. Fig. 50 8 is a detail view.

Referring to the drawings, the bend or connection is cast in one piece and comprises a horizontal member 9 which is connected to 50 the drainage system and an upright member 10 which is connected to the closet bowl 11 (Fig. 4). The upright member has an integral cap 12 which is connected with the upright member by a contracted neck 13 and 55 projects beyond said neck to provide, in effect, a peripheral flange 14 (Fig. 3). A

screw plug 15 is arranged in the cap for a purpose hereafter described. The horizontal member has a plurality of grooves 16 spaced apart at suitable intervals beginning 60 at its end which will facilitate cutting down the bend or connection to fit the system. The horizontal member can be cut at any one of the grooves very easily by using a chisel and hammer. The upright member 65 has a plurality of peripheral flanges 17 spaced apart at suitable intervals. The upright member is contracted just above each flange 17 to form a neck 18 (Fig. 5) to facilitate cutting down the upright member to 70 the proper height for connection with the closet bowl. To form the necks I prefer to provide the upright member with a peripheral groove 19 on its exterior and just above each flange and to recess or round off the interior of the upright member at 20 opposite 75 each groove. By inserting a chisel in any of these grooves 19 and applying a hammer the upright member can be cut evenly on the line of the groove to reduce the upright 80 member to the proper height for any particular installation. The gasket 21 is arranged between the upright member and the closet bowl and the rounded surface at 20 on the interior of the upright member provides 85 a proper seat for the gasket.

The closet bowl is connected and locked to the bend or connection by a bolt 22 which passes through a slot 23 in the flange 24 on the bowl. The bolt has an enlarged or offset 90 head 25 (Fig. 8) which is adapted to fit between two of the flanges on the upright member 10 (Fig. 5) and it is secured in these flanges by a pin 26 which seats in alined openings 27 in the flanges and an 95 opening 28 in the bolt head 25. Two bolts are usually employed and in assembling the parts, after the upright member has been cut down to fit the floor and made ready to have the closet bowl fitted or set in place, the 100 bolts are first fastened to the bend or connection, as shown, and then the bowl is set. After these parts have been properly positioned the nut 29 on each of the bolts is 105 tightened to lock the parts together.

While it is preferable to arrange the bolt head between the top and the next adjacent flange, as shown in Fig. 5, this is not essential because it will be readily seen that the bolt head could be put between the second 110 and third or any of the other flanges if it is long enough to project up through the flange

of the closet bowl to receive the nut. A washer 30 is arranged between the flange 24 of the closet bowl and the nut. This construction permits the bowl to swing in a considerable arc without engaging the flanges on the upright member of the bend or connection and this is important because it frequently happens that the slot in the flange of the closet bowl is irregularly formed or inaccurately positioned. This freedom of adjustment of the bowl greatly facilitates the connection of the closet bowl and the bend or connection. Beneath the lowest flange I provide two lugs 31 on the upright member of the bend or connection to be used when said member is cut down to the bottom flange and these lugs are bored to receive the pins 26 as before described.

20 I contemplate making the bend or connection as a stock article because it is adapted to be readily cut to fit different installations according to the particular conditions of each. After the bend or connection has been connected with the drainage system in a building and the stack completed the whole system can be filled with water for the water test. The inspector can ascertain at any time whether the bend or connection is filled with water by removing the plug 15.

My invention avoids the necessity for employing plugs to close the end of the upright member which heretofore has been left open and also avoids the liability of these plugs being blown out or becoming disarranged while the test is being conducted. It has been customary to leave the stack filled with water over night in performing the test and it happens with more or less frequency that the plugs are forced out or are deliberately or accidentally knocked out during this period. This necessitates a re-test which involves considerable delay and annoyance. After the test is completed and while the building is being finished, plastered and the floors laid, the cap 12 is permitted to remain on the bend or connection. This continues the seal and prevents the bend or connection from being filled and clogged with rubbish which frequently creates a great deal of trouble. After the floor of the building has been laid and it is time to set the closet bowl in place the cap 12 is removed by the use of a chisel and hammer and the upright member is cut down to a proper height in the same manner. Then the closet bowl is secured in place.

My invention provides a bend or connection of simple and inexpensive construction which greatly reduces the cost and facil-

tates the installation of the plumbing system in a building. It provides a permanent seal for the bend or connection until it is time to set the closet bowl and thus enables the test to be conducted to better advantage and avoids the liability of the drainage system being clogged with rubbish entering through the bend or connection. 65

The integral cap on my improved bend or connection prevents the escape of sewer gas 70 after the bend or connection is installed in the drainage system and while the building is in course of erection and completion.

What I claim and desire to secure by Letters Patent is:

75 1. A closet bend or connection having at one end and on the exterior thereof a plurality of peripheral grooves, the interior of said bend or connection being recessed and rounded opposite each of said grooves to facilitate cutting the bend or connection along the line of a groove and to form a gasket seat.

2. A closet bend or connection having at one end a plurality of peripheral flanges 85 spaced apart and a bolt having a head adapted to be engaged between any pair of the flanges.

3. A closet bend or connection having at one end a plurality of peripheral flanges 90 spaced apart, a contracted neck adjacent to each flange, and a bolt having a head adapted to be engaged between any pair of the flanges.

4. A closet bend or connection having at 95 one end a plurality of peripheral flanges provided with aligned openings, a bolt having an offset head adapted to be engaged between any pair of flanges and provided with an opening to align with the openings 100 in said flanges, and a pin to fit in said openings and pivotally connect the bolt with the bend or connection.

5. The combination of a closet bowl having a flange and a slot in said flange, of a bend or connection having at one end a plurality of peripheral flanges provided with aligned openings, a bolt having an offset head to fit between any pair of flanges and to project up through the slot in the closet 110 bowl flange, a pin engaging the flanges and the head of the bolt to pivotally connect the bolt to the bend or connection, and means for securing the bolt to the flange on the closet bowl.

FRANK W. CARLSON.
